PIERRE MALAVAL AND RENÉ PAUL EUGÉNE PAQUELIER, OF PARIS, FRANCE.

REMOVABLE LINER FOR GUNS.

Application filed May 6, 1922. Serial No. 558,994.

To all whom it may concern:

Be it known that we, PIERRE MALAVAL and RENÉ PAUL EUGÉNE PAQUELIER, citizens of the Republic of France, residents of 5 Paris, France, have invented new and useful Improvements in Removable Liners for Guns, which invention is fully set forth in the following specification.

This invention has for its object a process 10 for renovating worn gun barrels and modifications in the internal arrangements of gun barrels by lining the bore of the gun barrel.

In gun barrels as constructed hitherto the inner tube which constitutes the liner of 15 the gun immediately surrounding the bore of the gun, is assembled with the outer elements by transverse tightening, that is to say, before the assembling, the external diameter of the liner is greater than the internal diameter of the hooping or reinforcing element.

When the bore is worn, it is necessary to remove this liner which is fairly thick, either by destroying same in the lathe, or 25 by heating the outside of the gun barrel and cooling the liner; this process however is never successful in the case of gun barrels of large and medium calibres.

Afterwards, if it is desired to renovate 30 the gun barrel, the elements must be assembled afresh with a new liner. This operation requires approximately nine months in the case of a large gun barrel with the methods commonly in use.

35 In gun barrels as hitherto constructed in which there is a transverse compression as above defined, this compression is a positive stress, that is to say, the difference between the external diameter of the inner tube and the internal diameter of the hooping or reinforcing element is a positive quantity.

The process forming the subject matter of the present invention consists in constituting the liner of the gun barrel by means 45 of a thin lining tube which is assembled with the encircling elements of the gun barrel without any compressive stress, that is to say, at the time of assembling the elements together, there exists a diametral 50 "play" between the thin lining tube and the encircling elements.

Further, the lining tube is made of a metal having a suitable elastic limit such that 55 the said "play" which is absorbed at the instant of firing the gun, reappears in the

"state of rest" (that is after the firing of the gun) and subsists indefinitely.

The desired elastic limit is determined in the following manner:

Let j be the "play" (or negative compression), r the outside radius of the thin lining tube, R_0 the inside radius of the gun barrel, R_1 the outside radius of the gun barrel.

Δt the difference between the tensile stress which exists in the outer layer of the thin lining tube during the "state of rest", and the firing tensile stress in the same outer layer produced by the firing of the gun.

$\Delta t'$ the difference between the tensile stress which exists in the inner layer of the bored gun barrel, during the "state of rest", and the firing tensile stress in the same inner layer.

P_0 the pressure in the bore,
 P_1 the pressure in the "radial play" space,
 E the elastic limit of the metal,
 M the modulus of elasticity and the interior of the thin lining.

T_0 the "firing tensile stress" (that is, the tension caused by the explosion of the gun charge) in the tube.

Then the compressive stress is represented by:

$$j = \frac{r}{M} (\Delta t - \Delta t') \quad 85$$

But

$$\Delta t = P_1 \frac{R - R_0^2}{R - r^2} \quad 90$$

On the other hand, we have these two fundamental relations, namely:

$$\Delta t' - P_1 = T_0 - P_0$$

$$(\Delta t' - P_1) r^2 = (T_0 - P_0) R_0^2 \quad 95$$

Now in order that the thin lining tube shall not be deformed, it is necessary to bring in the relation:

$$T_0 - P_0 = E \quad 100$$

These five equations with the five unknown quantities:

Δt , $\Delta t'$, P_1 , T_0 and E give E .

In order to withstand any deformation and any longitudinal shifting of the thin lining tube as well as any torsion of the latter due to the effect of the friction of the projectile and the action of the rifling grooves etc., the thin lining tube and the

bore of the gun barrel are provided with any suitable projections, shoulders, nibs, keys, etc., arranged as far as possible in such a manner as not to interfere with the 5 removal of the thin lining tube.

The accompanying drawings illustrate by way of example a constructional form of a thin lining tube and a lined gun barrel according to this present invention.

10 Figure 1 is an elevation of the thin lining tube; and

Figure 2 is a longitudinal section of a gun barrel fitted with the thin lining tube shown in Figure 1.

15 1 is a thin lining tube made of gun metal of high elastic limit, and 2 are shoulders situated about one metre apart along the outside of the said thin lining tube in the region corresponding to the rifling of the 20 bore. These shoulders are designed to resist the permanent elongation of the thin lining tube due to the effect of the firing of the gun, and also overcome any tendency to 25 force the thin lining tube towards the muzzle end of the gun barrel.

The thin lining tube is also provided with tongues 3 or sectors intended to resist the permanent torsion which tends to be produced by the passage of the projectile.

30 4 is a ring or sleeve for reinforcing the breech; it is screwed cold upon the gun barrel 5 and has a constant tendency to force the thin lining tube towards the muzzle end of the gun barrel.

35 6 is the "play" (or negative compression) provided between the thin lining tube and the gun barrel 5.

The improved process is applicable to gun 40 barrels made in one piece whether they are given an initial set by hydraulic compression or not; also to ordinary hooped or reinforced gun barrels; and likewise to gun barrels made of more than one piece having initial set by compression; in a word, the 45 improved process is applicable to all gun barrels.

A modification of the process consists in reducing or even in doing away altogether 50 with the "play" after the liner has been placed in position, by longitudinal compression between the breech ring or sleeve and the shoulders hereinbefore referred to.

In all cases the improved process has the 55 following advantages:—

1. Instead of requiring many months for retubing or relining a gun barrel in a special factory furnished with lathes, boring machines, tube-fitting trenches, and hoisting appliances, this operation can be 60 done in a few minutes at proving grounds at any spot; on board-ship for small and medium calibres; in a harbour for warships; in an artillery park of an army division for field guns, and in case of necessity in the 65 battery position for entrenched guns. The

improved process requires only a few minutes, as a matter of fact it is merely necessary to unscrew the breech ring or screw 4 that has been put on cold.

2. Worn gun barrels can be renovated at 70 small cost.

3. Old gun barrels can be reconstructed internally for receiving the improved thin lining tube according to this invention, and thus be converted into new gun barrels of 75 the latest model.

4. The amount of steel which is necessary for relining gun barrels according to this invention, is very small so that gun-makers need no longer fear a deficiency in the available quantity of such steel in time of war. 80

5. The power of old gun barrels can be increased because they can be given an initial stress or set by hydraulic compression before being relined. 85

6. If the type of powder that is used at present should become replaced by a more powerful type, old gun barrels may still continue to be used owing to the employment of the improved lining tube. 90

Claims:

1. A gun comprising, in combination, a barrel and an elastic metal lining tube within in the bore of the barrel, the diameter of the bore of said barrel and the external diameter of the tube being so proportioned that the barrel confines said tube within its elastic limits under the stress of fire while leaving play between the tube and barrel when relieved of such stress, whereby said tube is 100 easily removable. 105

2. A gun comprising, in combination, a barrel, an elastic metal lining tube within the bore of the barrel, the diameters of the bore of the barrel and the exterior of the tube being so proportioned that the barrel confines the tube within its elastic limits under the stress of fire while leaving play between the tube and barrel when relieved of such stress, whereby the tube is rendered 110 easily removable, and means restraining said tube from longitudinal movement within the bore. 115

3. A gun comprising, in combination, a barrel, an elastic metal lining tube within the bore of the barrel, the diameters of the bore of the barrel and the exterior of the tube being so proportioned that the barrel confines the tube within its elastic limits under the stress of fire while leaving play between the tube and barrel when relieved of such stress, whereby the tube is rendered 120 easily removable, and means restraining said tube from circumferential movement within the bore. 125

4. A gun comprising, in combination, a barrel, an elastic metal lining tube within the bore of the barrel, the diameters of the bore of the barrel and the exterior of the tube being so proportioned that the barrel 130

confines the tube within its elastic limits under the stress of fire while leaving play between the tube and barrel when relieved of such stress, whereby the tube is rendered
5 easily removable, and a reenforcing sleeve around the breech end of the barrel and confining the tube within said barrel.

5. A gun comprising, in combination, a barrel, and an elastic metal lining tube with-
10 in the bore of the barrel, said tube being provided with a plurality of exteriorly formed annular shoulders of different diameters engaging corresponding shoulders within the bore of the barrel, the diameter
15 of the bore of said barrel and the external diameter of the tube throughout their lengths being so proportioned that the barrel confines said tube within its elastic limits under the stress of fire while leaving play
20 between the tube and the barrel when relieved of such stress, whereby said tube is rendered easily removable.

6. A gun comprising, in combination, a barrel having a plurality of shoulders formed interiorly thereof, and an elastic metal lining tube having shoulders formed

exteriorly thereof for engagement with said first-named shoulders when the liner is associated with said barrel, whereby the movement of the liner toward the muzzle of the
30 gun is prevented, and a reenforcing sleeve surrounding the exterior of the breech end of the barrel and engaging said lining tube, the external diameter of the tube and the diameter of the bore of the barrel being so proportioned that the barrel confines said tube within its elastic limits under the stress of fire while leaving play between the tube and barrel when relieved of such stress
35 whereby said tube is easily removed.

7. A liner for a gun comprising a metal tube provided with a plurality of exteriorly formed annular shoulders of different diameters, and a plurality of teeth formed one adjacent each of said shoulders, said
40 shoulders being concentric and laterally spaced apart.

In testimony whereof we affix our signatures.

PIERRE MALAVAL.
